ORNAMENTAL RIBBON

John R. Sexton and Joseph A. Vivari, Meriden,
Conn., assignors to J. R. Sexton Incorporated,
Meriden, Conn., a corporation of Connecticut

Application June 5, 1936, Serial No. 83,644

8 Claims. (Cl. 117—60)

This invention relates to the manufacture of ribbon or cord provided for tying packages and boxes which it is desired shall present an attractive and ornamental appearance.

The object of this invention is the production of a flexible ribbon or cord which is simple to manufacture, is strong, and that will have a brilliant and scintillating luster and sparkle.

This end is attained broadly, by forming a laminated body or core of a plurality of superposed strips, the outer strips being of transparent or colored or tinted translucent, flexible cellulose material which has a smooth, glossy, moisture-proof surface, such for example as "cellophane" or "celanese", and the inner strip or strips being of light reflecting material such as a lahn or tinsel, and binding together these strips by an open spiral winding of lahn or of twisted or woven fibrous material, as rayon, which binding yarn tends to crinkle the strips with the result that the inner strip reflects light through the outer strips and the desired sparkle produced.

In the accompanying drawing the invention is illustrated on greatly enlarged scale.

Fig. 1 shows a front view of three superposed strips, an inner lahn strip and two outer cellulose strips, before a winding is applied.

Fig. 2 shows an edge view of the same.

Fig. 3 is a view showing the strips bound together by a tensioned winding of a rayon yarn.

Fig. 4 shows an edge view of a section of the wound strip.

Fig. 5 shows a front view of a modified arrangement of strips before winding.

Fig. 6 shows an edge view of the unwound strips.

Fig. 7 is a view of the last mentioned strips bound together by a loose winding.

Fig. 8 is a transverse section showing a plurality of inner strips and wider outer strips, before being wound.

Fig. 9 is a similar view showing the strips indicated in Fig. 8, bound together by a yarn winding.

In the particular embodiment of the invention first illustrated the core of the ribbon has a narrow center strip 1 of thin opaque bright or shiny lahn or metal tinsel. Each side of the center strip is a thin wider strip 2 of transparent or translucent cellulose material, such as "cellophane" or "celanese". The outside strips may have the same tint or color, preferably the same. Wound in an open spiral about and binding these strips together is a fine thread or yarn 3 of rayon. The winding may have the same or different tint or color as the outer strips, desirably the same. The tension of the winding is by choice such as

to crimp or scallop the edges of the strips and cause the sections intermediate the windings to bulge or swell out and become wave-like. As a result of such distortion of the core light is reflected from the ruffled inner strip at various angles through the waved outer strips and is radiated as if thrown off by facets, the inner bright strips accentuating the brilliancy of the rays reflected from the glassy surfaces of the tinted or colored cellulose strips.

In the second embodiment of the invention illustrated the center strip 4 and the outer cellulose strips 5 are of the same width and the thread or yarn winding 6 is not tensioned as tightly as the winding of the above described ribbon. In this case the light rays flash brightly from the reflecting strip through the cellulose strips between the windings, but the ribbon does not have the sparkle that results from tight windings which crinkle the core.

Instead of having a single central strip between the surface strips there may be a number of intermediate strips 7, and the outside strips 8 may be somewhat wider than the inside strips, in which case when the thread or yarn 9 is wound tightly about the core the edges of the wide strips are puckered inward and thus the edges as well as the flat faces are crinkled or scalloped so as to reflect light rays at different angles.

A ribbon formed according to this invention is flexible and has considerable tensile strength, and can be readily tied in plain knots or fancy bow knots.

The invention claimed is:—

1. A ribbon having a laminated body comprised of flat outer strips of thin flexible light transmitting cellulose material and an inner strip of thin flexible light reflecting material, said strips being bound together and crinkled by an open spiral winding of flexible material.

2. A ribbon having a laminated body comprised of flat outer strips of thin flexible light transmitting cellulose material and an inner strip of thin flexible metallic material, said strips being bound together and crinkled by an open spiral winding of fibrous material.

3. A ribbon having a laminated body comprised of flat outer strips of thin flexible light transmitting cellulose material and an inner strip of thin flexible light reflecting material, said strips being bound together tightly and crinkled by an open spiral winding of fibrous material.

4. A ribbon having a laminated body comprised of flat outer strips of thin flexible light transmitting cellulose material and an inner strip of thin

flexible light reflecting material that is narrower than the outer strips, said strips being bound together and the edges of the outer strips crushed against the inner strip by an open spiral winding of fibrous material.

5. A ribbon having a laminated body comprised of flat outer strips of thin flexible light transmitting cellulose material and inner strips of thin flexible material, said strips being bound together 10 and crinkled by an open spiral winding of fibrous material.

6. A ribbon having a laminated body comprised of flat outer strips of thin flexible light transmitting material separated by thin flexible opaque 15 material, said strips being bound tightly together.

and crinkled by an open spiral winding of fibrous material.

7. A ribbon having a laminated body comprised of flat outer strips of thin flexible light transmitting material separated by thin flexible opaque 5 light reflecting material, said strips being bound together by an open spiral winding of lahn.

8. An ornamental ribbon having a laminated body comprised of strips of flat thin flexible light transmitting material and a flat strip of thin 10 flexible light reflecting material, bound together and crinkled by an open spiral winding of flexible material.

JOHN R. SEXTON.
